ATTORNEY

UNITED STATES PATENT OFFICE.

ALBERT H. WAGNER, OF BONNER, MONTANA.

RIPPER HEAD.

Application filed April 13, 1927. Serial No. 183,522.

My present invention has reference to a lumber ripping device, and the object of the invention is the provision of a cutter head which may be readily arranged upon a saw shaft or arbor and which includes a pair of discs having their confronting faces formed with pockets for the reception of the ends of radially extending knives and wherein the said knives are set at a slight angle with respect to the central line therebetween to provide a clearance so that the knives will not become overheated in the cutting operation, and further wherein the construction of knives is such as to afford smooth edges to the lumber operated thereon.

A further object is the provision of a cutter head for this purpose that is of an extremely simple construction, may be cheaply manufactured and arranged in operative position, and wherein the cutter head is provided with pockets disposed at opposite angles for the reception of cutting knives which radiate from the head whereby a space or clearance is maintained between the knives, so that the alternately arranged knives will act upon the opposite edges of the kerf made thereby and will not contact with the wood operated on with sufficient friction to cause the overheating of the knives, so that the life of the cutter head is thus materially prolonged and further wherein the knives are straight throughout the length thereof and may be removed or replaced for sharpening or renewal.

To the attainment of the above broadly stated objects and others which will present themselves as the nature of the invention is better understood, the improvement also resides in certain other novel features of construction, combination and operative association of parts, a satisfactory embodiment of which is disclosed by the accompanying drawings.

In the drawings:

Figure 1 is a face view of a cutter head in accordance with this invention.

Figure 2 is an approximately central longitudinal sectional view therethrough.

Figure 3 is an end view thereof.

Figure 4 is a detail sectional view approximately on the line 4—4 of Figure 1.

In carrying out my invention I preferably employ a bushing 1 that has one end flanged outwardly and that is provided with one or more longitudinal grooves 2. These grooves allow a sleeve, hereinafter referred to to

contact with the bushing when a nut, that threadedly engages the bushing is adjusted thereon. The bushing is clamped on a saw shaft or mandrel in the usual manner. Fixedly arranged on the bushing and contacting with the flange on the outer end thereof there is a sleeve 3 which also has an outer flange 4. Screwed on the bushing 1 and contacting with the sleeve 3 there is a nut 5.

Arranged on the sleeve 3 for turning therewith there is a pair of discs 6 and 7 respectively. Each of these discs is of soft metal, and each of these discs has its confronting face milled to provide pockets 8 for the cutting knives. The alternating pockets 8 are disposed at opposite angles so that the ends of the pockets nearest the center of the head are disposed away from the opposite sides of the pockets a distance of approximately $\frac{3}{8}$ of an inch. In each of these pockets there is the inner straight end of cutter blades 9. Of course, the blades are of the same length. Each blade has one of its corners rounded to form the same with a cutting edge 10 and the outer ends of the cutter blades are cut at the same angle, as indicated by the numeral 11. There is screwed on the sleeve 3 a nut 14 that contacts with the inner disc 6 for holding both of the discs in contacting engagement with each other and the outer disc 7 tight against the flange 4. The nut 14 is formed on its upper face with a flange 15 provided with wrench surfaces which is true with respect to the nut 5.

The outer soft metal disc 7 has radial kerfs or slots 16 in a line with the center of the pockets formed in the said discs, and between these kerfs there are threaded headed screws 17 that connect the discs. Obviously the kerfs weaken the outer face of the disc 7 so that when the heads of the bolts are screwed thereagainst the inner face of the disc will be compressed or in other words brought into tight contact with the inner face of the discs 6 so that the knives are positively pocketed between the discs.

A cutter head constructed as above described insures a free and smooth cutting of the lumber. This in itself involves a material saving in time and labor, as with the ordinary means for ripping lumber the slit or kerfed edges thereof are left rough while with my construction these edges are nicely planed. By arranging the knives at a slight angle with respect to the central line of the head the alternating knives will engage with

the opposite walls provided by the kerf or cut and the clearance spaces between the knives prevent the overheating of such knives so that the knives will not burn and the life thereof is materially prolonged. The cutting blades or knives are straight throughout the length thereof and the outer angle ends will prevent marking or scratching of the edge of the lumber.

10 Having described the invention, I claim:—

A rotary lumber ripper, including two discs of soft metal, each of said discs having their inner faces at equidistantly spaced

intervals provided with radially disposed pockets, and the alternating pockets being arranged at slight opposite angles with respect to each other, a straight cutter blade received in each pocket and radiating from the discs, one of said discs having its outer face provided with radial kerfs disposed in a line with the central members and headed bolt members having their shanks passing through the discs and arranged between the kerfs.

In testimony whereof I affix my signature.

ALBERT H. WAGNER.
